Inventor

UNITED STATES PATENT OFFICE.

HARRY F. OLLIS, OF EAST LEXINGTON, MASSACHUSETTS.

DESIGN FOR A BRACKET FOR PILLOW-SHAM HOLDERS.

58,619.

Specification for Design.

Patented Aug. 2, 1921.

Application filed December 15, 1920. Serial No. 430,967. Term of patent 14 years.

To all whom it may concern:

Be it known that I, HARRY F. OLLIS, a citizen of the United States, residing at East Lexington, in the county of Middlesex and State of Massachusetts, have invented a new, original, and ornamental Design for Brackets for Pillow-Sham Holders, of which the following is a specification, reference being had to the accompanying drawing, forming part thereof.

The figure is a plan view of a bracket for pillow sham holders showing my new design.

I claim:

The ornamental design for a bracket for pillow sham holders as shown.

December 13, 1920.

HARRY F. OLLIS.

Witness:

HERMAN BIRD.
